UNITED STATES PATENT OFFICE

2,459,882

SWINGING JAW ADJUSTABLE WRENCH

Rollie Johnson, Edgerton, Mo.

Application February 17, 1947, Serial No. 729,109

1 Claim. (Cl. 31—99)

1

This invention relates to tools and has for its primary aim the provision of an adjustable wrench having a swingable and a slidable jaw mounted in opposed relation on an elongated body whereby an article may be gripped between said jaws when the same are shifted relatively toward each other.

The most important object of this invention is to provide in a wrench having the aforesaid swinging jaw as a part thereof, an extension on the jaw projecting laterally from one edge thereof to cooperate with a pair of mounting ears in forming a fulcrum for the jaw spaced from its supporting body. A still further object of this invention is the provision of a swinging jaw adjustable wrench having a slidable jaw movable in a rectilinear path of travel substantially parallel to the longitudinal axis of the body and toward and from the said swingable jaw.

Many minor objects will be made clear during the course of the following specification, reference being had to the accompanying drawing wherein:

Figure 1 is a side elevational view of a swinging jaw adjustable wrench made in accordance with my present invention.

Fig. 2 is an inverted plan view thereof.

Fig. 3 is a fragmentary top plan view thereof.

Fig. 4 is a cross sectional view taken on line IV—IV of Fig. 1 and looking in the direction of the arrows and

Fig. 5 is a cross-sectional view taken on irregular line V—V of Fig. 1.

In the drawing a body designated by the numeral 10 has a handle 12 on one end thereof and a pair of spaced apart sleeves 14 and 16 extending laterally from one edge 18 thereof for slidably receiving a jaw 20. These sleeves 14 and 16 are provided with aligned openings 24 and 22 respectively through which jaw 20 is loosely and slidably disposed. This jaw 20 has external threads 26 thereon for receiving an internally threaded nut 28 disposed in the space between sleeves 14 and 16. It is clear therefore that turning of this nut 28 will cause the jaw 20 to move toward and from the ends respectively of body 10 in a rectilinear path of travel substantially parallel with the longitudinal axis of the body 10.

One end of the jaw 20 is provided with a serrated head 30 cooperable with a head 32 of a swingable jaw broadly designated by the numeral 34. This swingable jaw 34 is substantially L-shaped, one leg thereof formed by the head 32 which is also serrated in the usual manner as illustrated in Fig. 1.

2

Body 10 is provided with a pair of spaced-apart ears 36 and 38 which ears extend laterally from edge 40 of body 10 and near one end 42 thereof remote from handle 12. These ears 36 and 38 are triangularly shaped and are provided with bores 44 near the apex thereof for receiving a pin 46. One leg 48 of the swinging jaw 34 is substantially rectangularly shaped and this leg 48 is interposed between the fingers 36 and 38 of body 10. An extension 50 projects laterally from this leg 48 and is disposed on the normally outermost edge thereof and intermediate its ends. This extension 50 is circularly bored as at 52 to pivotally receive the pin 46.

15 A leaf spring 54 is secured to the body 10 on edge 40 thereof by a screw or the like 56 and this spring 54 has its free end disposed between the leg 48 of the jaw 34 and the edge 40 of body 10 to yieldably hold leg 48 in spaced relation to body 10. The head 32 of jaw 34 overlaps the end 42 of body 10 and extends a distance beyond the edge 18 of body 10 in the path of travel of the sliding jaw 20.

20 It is clear that as any object is disposed between the serrated edges of heads 32 and 30 of jaws 34 and 20 respectively and as jaw 20 is caused to be moved toward the end 42 of body 10 such object will be firmly grasped therebetween. The spring 54 will maintain head 32 of jaw 34 in contact with the article being handled through the pivotal section of leg 48 on the ears 36 and 38.

25 The fulcrum point for this jaw 34 being remote from the edge 40 of body 10 and this jaw 34 being disposed in opposed relation to the sliding jaw 20, it is clear that a strong and extremely efficient adjustable wrench has been provided. This jaw 34 is disposed where the same will not likely cause interference when the same is placed in use and the free action thereof presents a highly efficient wrench and one that will react positively whenever placed in use and not likely to get out of order or be easily damaged.

30 Many advantages will arise through employment of the swinging jaw adjustable wrench just described and those advantages are contemplated hereby. It is therefore desired to be limited only by the spirit of this invention and scope of the appended claim.

Having thus described the invention, what is claimed as new and desired to be secured by Letters Patent is:

35 A wrench comprising a body having a handle on the rear end thereof; a pair of longitudinally spaced and transversely extending sleeves 55 projecting from one edge of the body between

the ends thereof and having longitudinally aligned apertures therein, a slideable jaw movable toward and away from the forward end of the body and having a threaded shank positioned within said sleeve apertures, a nut on said shank and positioned in the space between said sleeves, a swingable jaw on the opposite edge of the body having a head overlapping said forward end of the body in close proximity thereto, said head of the swingable jaw extending into the path of travel of said threaded shank, a pair of transversely spaced and longitudinally extending triangular ears projecting from the opposite edge of the handle and at the forward end of the body, said swingable jaw having a rigid shank positioned between said ears and pivotally joined to

that apex of each ear remote from said opposite edge, said remote apexes lying in a transverse plane passing through the body substantially midway between the forward end of the body and the forwardmost sleeve.

ROLLIE JOHNSON.
